UNITED STATES PATENT OFFICE.

EDWIN H. SWIFT, OF BROOKLYN, NEW YORK.

AIR HEATER AND INDUCER FOR FURNACES.

Application filed July 18, 1923. Serial No. 652,362.

To all whom it may concern:

Be it known that I, EDWIN H. SWIFT, a citizen of the United States, and resident of the borough of Brooklyn, city of New York, in the county of Kings and State of New York, have invented certain new and useful Air Heaters and Inducers for Furnaces, of which the following is a specification.

10 This invention relates to an air heater and inducer for a furnace.

The object of the invention is the production of a device and a method, by means of which heated air is supplied to the unconsumed products of combustion of the fuel of a furnace to secure complete combustion. A second object of the invention is to provide heated air to the burning fuel of a furnace at a velocity of inflow, by means of 20 which the oxygen of the inflowing air will combine with the unconsumed gases generated, and therefore not chill the bed of the fuel in the furnace. A third object of the invention is the production of means and steps 25 whereby all portions of an inflow of air to the combustion chamber of a furnace is heated, before mixing with the gases generated therein. A fourth object of the invention is to prevent the escape of obnoxious gases from the combustion chamber of a furnace. A fifth object of the invention 30 is to provide means, whereby an inflow of air for the combustion chamber of a furnace is discharged therein in all portions thereof.

The organization of the invention comprises an induction tube for an inflow of air, adjustably connected to the door of a furnace and of a length to enable the air that flows therethrough, to be discharged between the axial center of the furnace and the front wall thereof. A heating coil is located in the tube to give the inflowing air a twirling movement, and openings are 40 formed in the induction tube for the inflow of heated air and gases to the inside of the said tube, to mix with the air flowing therethrough, before entering the combustion chamber of the furnace, in addition to the heat that is transmitted from the fuel of the furnace through the wall of the induction tube.

In the accompanying drawings Fig. 1 represents a vertical axial section of a portion of a furnace, with a side elevation of the air heater and inducer, indicated in full

lines in its operative position, with the barrel of the latter indicated in its withdrawn position in dotted lines, Fig. 2 shows an enlarged top plan view of the air heater and inducer; Fig. 3 indicates a partial section of Fig. 2 on the line 3, 3; Fig. 4 represents a left hand side view and section of Fig. 3 on the line 4, 4 and Fig. 5 shows a section of Fig. 3 on the line 5, 5.

In general terms the air heater and inducer comprises an induction tube designated in its entirety by the letter A, which has detachably connected thereto at its outlet end the flared outlet nozzle designated in its entirety by the letter B. A heating coil designated in its entirety by the letter C, is detachably secured within the induction tube. The induction tube A is detachably supported upon the arcuate support designated in its entirety by the letter D, and is detachably fastened to the door of the furnace for which the air heater and inducer is used.

A furnace is indicated in its entirety by the letter F, and comprises the combustion chamber 20, the grate 21, the front wall 22, the rear wall 23, the ash pit 24, the furnace door 25, the furnace door opening 26, the ash pit door 27, and the ash pit door opening 28.

The induction tube A is preferably cylindrical and has formed therewith at one end the flared inlet nozzle 30. Rectangular inlet openings 31 are formed in the lower position of the tube A and openings 32 are formed in its sides, while pairs of openings 33, 34, 35 and 36 are formed in the crown and bottom of said tube. A damper 38 is provided for the tube A adjacent to the inlet nozzle 30. The damper is supported on the spindle 39, the ends of which are journaled in the wall of said tube. An operating knob 40 is fastened to the lower end of the spindle 39; and an arm 41 with an extension 42 is fastened to the other end of the said spindle. Longitudinal supporting and track flanges 43, extend from the sides of the tube A and a bearing disc flange 44 also extends from said tube.

The flared outlet nozzle B has formed therewith the sleeve 45 having openings 46. A split pin 47 extends through the openings 46, and in this instance through the openings 35, 36 of the tube A, to detachably secure the nozzle B to said tube.

The heating coil C in this instance com-

prises a core of a pair of wires 48, 49 wound on each other and has formed at one end an eye 50 used for handling the coil, while adjacent to the other end is formed a second eye 51. The coil in this instance is double threaded and consists of a series of rings 54 extending from its core. The rings follow each other in a helical direction in said induction tube A, from adjacent to the door 25 of the furnace F to the outlet end of the tube. It will be noted that the rings 54 of the coil extend beyond the eye 51. The pin 47 extends through the eye 51.

The arcuate support D comprises the arcuate member 60 which extends from the front plate 61. The latter has formed therewith the annular flange 62 which terminates at one end in the hinge member 63, and at the other end in the stop lug 64. An annular locking ring 68 has extending therefrom the annular locking flange 69, and an operating lug 70 with the locking shoulder 71 is formed with the locking ring 68. The locking ring 68 is hinged to the hinge member 61 by means of the hinge bolt 72, which latter also extends through the door 25.

The front plate 61 is fastened to the furnace door 25 by means of the bolts 74.

The induction tube A is seated in the arcuate member 60 of the arcuate support D, with its flange 44 bearing against the outer face of the front plate 61 above the annular flange 62.

The locking flange 69 of the locking ring 68 is swung to its closed position to lock in place the flange 44 of the tube A, the operating lug 70 being located beyond the stop lug 64.

To swing the door 25 of the furnace F to either its open or closed position, the flange 44 of the tube A is unlocked from the door 25, by swinging up the annular locking ring 68, and moving the induction tube outwardly as indicated in dotted lines in Fig. 1, so that the outlet nozzle B will clear and swing in the furnace door opening 26.

To use the air heater and inducer, the door 25 of the furnace F is opened and the induction tube A is located upon the supporting and track flanges 43 of the arcuate support D, in its withdrawn position as indicated in dotted lines in Fig. 1, after which the door 25 is closed. Next the locking ring 68 is swung to its closed position so that the locking flange 69 thereof will lock the disc flange 44 of the induction tube in place. The length of the said induction tube is preferably made to locate the outlet end of the outlet nozzle B, between the axial center of the furnace and its front wall 22. The damper 38 is now swung open to permit the required volume of air to flow through the induction tube into the combustion chamber 20 at the requisite velocity. The air as it

flows through the induction tube A in a stream is twirled in various directions, by means of the heating coil C. At the same time streams of heated air and heated gases from the combustion chamber 20 flow 70 through the openings 31 and 34 in the bottom of the tube A, pierce and flow through the heating coil C and the main portion thereof flows with the induced air from the outside of the furnace through the outlet 75 nozzle B. Some of the heated air in the induction tube is discharged therefrom through the openings 32 and 33. By this means the induced air is thoroughly heated 80 throughout all portions thereof, before it enters the combustion chamber 20 of the furnace F, and is delivered in proper condition therein, for the combustion of its oxygen with the unconsumed gases of the products of combustion. By this means 85 perfect combustion is obtained with a great saving of fuel and obnoxious gases are prevented from escaping from the furnace. The arcuate support D slidably supports the induction tube A, so that the outlet 90 end of the outlet nozzle B can be located between the axial center of the furnace F and its front wall, to distribute the stream of induced air to all portions of the combustion chamber 20, and to be enabled to locate 95 said induction tube in its withdrawn position, when the door 25 of the furnace is to be opened or closed.

It will be noted that the heating coil C in the induction tube A is locked thereto some distance back from the outer end thereof, through the second eye 51, to be enabled to extend the windings of the coil to the outer end of the tube A. By this construction practically the whole heating value of 105 the coil is obtained.

Various modifications may be made in the invention without departing from the spirit thereof, and the present exemplification is to be taken as illustrative and not limitative. 110

Having described my invention what I desire to secure by Letters Patent and claim is:

1. In an air heater and inducer the combination of an induction tube extending through an opening in the door of a furnace, said tube having openings in its wall, an outlet nozzle detachably connected to the outlet end of the tube, a heating coil detachably secured in the induction tube said coil comprising a core with a series of rings extending therefrom, said rings following each other in a helical path, and means to detachably lock the induction tube to the door of the furnace. 115

2. In an air heater and inducer the combination of an induction tube extending through an opening in the door of a furnace, said tube having openings in its wall, an outlet nozzle detachably connected to the 130

outlet end of the tube, a heating coil detachably secured in the induction tube said coil comprising a core with a series of rings extending therefrom, said rings following each other in a helical path, a damper in the tube and a locking device to lock the induction tube to the door of said furnace.

3. In an air heater and inducer the combination of an induction tube extending through an opening in the door of a furnace, said tube having openings in its wall, an outlet nozzle for the tube, a helical heating coil in the tube extending from adjacent to the door of the furnace to the end of the tube said coil comprising a core with a series of rings extending therefrom, said series of rings following each other in a helical path, means to detachably lock the coil at a distance spaced from its end of the tube and 20 means to detachably lock the induction tube to the door of the furnace.

4. In an air heater and inducer the combination of an induction tube extending

through an opening in the door of a furnace and having a disc flange and supporting and track flanges extending therefrom and having openings in the wall thereof, an outlet nozzle detachably connected to the outlet end of the induction tube, a heating coil detachably secured in the tube, a plate with an annular flange fastened to the door of the furnace, an arcuate support extending from said plate through the opening in the door of the furnace and a locking ring with an annular locking flange hinged to said plate, 35 said induction tube located upon said arcuate support with its flanges bearing on the side edges thereof, and the annular flange of said plate and the flange of said locking ring locking the disc flange of the induction tube to the door of the furnace.

Signed at the borough of Manhattan, city of New York, in the county of New York and State of New York, this 28th day of June A. D. 1923.

EDWIN H. SWIFT.
